Specification for Design.

Patented Dec. 9, 1919.

Application filed September 3, 1919. Serial No. 321,473. Term of patent 14 years.

To all whom it may concern:

Be it known that I, WILLIAM S. STOTHOFF, a citizen of the United States, residing at Easton, in the county of Northampton and State of Pennsylvania, have invented a new, original, and ornamental Design for Tractor-Wheels, of which the following is a specification, reference being had to the ac-

companying drawing, forming a part hereof.

The figure is a perspective view of a tractor wheel, showing my new design.

I claim:

The ornamental design for a tractor wheel, as shown.

WILLIAM S. STOTHOFF.
